HOUSING FOR A CARPET SWEEPER

Howard A. Anderson, Pittsburgh, Pa., assignor to Bissel Inc., Grand Rapids, Mich., a corporation of Michigan

Filed Feb. 23, 1967, Ser. No. 5,919

Term of patent 14 years

(Cl. D49—15)

FIG. 2 is a top plan view thereof; and

FIG. 3 is an elevation view taken from the right end of FIGURE 1.

The side not shown is a mirror image of the opposite side.

I claim:

The ornamental design for a housing for a carpet sweeper, substantially as shown and described.
